L. T. TROLAND

CINEMATOGRAPHIC DEVICE

Filed August 7, 1923

Inventor:
Leonard T. Troland
By Robert Roberts & Cushman
Atty's

UNITED STATES PATENT OFFICE.

LEONARD T. TROLAND, OF MALDEN, MASSACHUSETTS, ASSIGNOR TO TECHNICOLOR MOTION PICTURE CORPORATION, OF BOSTON, MASSACHUSETTS, A CORPORATION OF MAINE.

CINEMATOGRAPHIC DEVICE.

Application filed August 7, 1923. Serial No. 656,175.

This invention relates to film-guide means for use in cinematographic machines and particularly to a film-guide for use in a machine (such as disclosed for example in 5 Serial No. 512,399, filed Nov. 2, 1921) for printing color film where the complementary images must be accurately positioned relatively to each other, the object of the invention being to guide the film smoothly 10 and accurately along a predetermined path and to provide a facile and precise adjustment of the guiding means.

For the purpose of illustrating the invention one concrete embodiment thereof 15 is shown in the accompanying drawings, in which:—

Fig. 1 is an end elevational view;
Fig. 2 is a front elevational view;
Fig. 3 is a plan view partly in section of 20 the roller and bracket; and

Fig. 4 is a rear elevational view of the parts shown in Fig. 3.

The embodiment of the invention shown 25 for the purpose of illustration comprises a guide roller A supported for rotation upon a bracket B in turn attached to any suitable support C along the film passageway of a printer or other cinematographic machine. The roller A has shoulders in the form of 30 end flanges 5 and a central reduced portion 6 so that only the edges and the marginal portions of a film D (Fig. 1) are engaged thereby as the film passes over the roller.

Roller A is mounted for free rotation upon 35 a shaft 7 supported in suitable bearings in spaced ears 8 and 9 projecting from the elongate bracket B. Roller A is held in fixed axial position upon shaft 7 by suitable means such as collars 10 pinned or 40 otherwise made fast to the shaft. Sufficient clearance is provided between collars 10 and ears 8 and 9 to permit axial adjustment of the roller. This axial adjustment is provided by a threaded opening for

45 shaft 7 in ear 9 and a threaded portion 7' upon the shaft to cooperate with the threaded opening. The end of shaft 7 adjacent the threaded portion has a cross-cut 11 to permit easy turning of shaft 7 by means of a screw-driver or other flat-blade tool. Shaft 7 is retained in adjusted 50 position by any suitable means such as a clamping screw 12 extending through

bracket B to engage the threaded portion of the shaft as indicated in Fig. 3. For 55 the purpose of strengthening bracket B, ribs 13 and 14 may be provided thereon and rib 13 may be enlarged in the form of a boss at 13' around the opening for the clamping screw 12. Bracket B may be 60 attached to its support C by screws or bolts 15 extending through openings 16 and 17 in the upstanding portions 18 and 19 of the bracket. Opening 17 is in the form of 65 a slot to permit angular adjustment of the bracket B, and hence of the roller A, upon support C.

In assembling the device the small end of shaft 7 is passed through the threaded opening in ear 9 and as it extends into the 70 space between ears 8 and 9 one of the collars 10 is first slipped thereover, then the roller A, then the other collar 10, and when the threaded portion of the shaft reaches ear 9 the shaft is screwed into position with 75 its reduced end passing through the bearing in ear 8. Collars 10 are then pinned or otherwise made fast to the shaft to retain the roller A in fixed position thereon. The 80 assembled device may now be mounted by 85 means of bolts or screws 15 upon the apparatus on which it is to be used, the slot 17 permitting angular adjustment of the bracket and roller. After the angular adjustment is properly made roller A may 85 be moved axially by turning shaft 7 with a screw-driver fitted to the end-cut 11 until roller A is accurately in position. Clamping screw 12 is then set up and the device 90 is ready for use.

The device is particularly useful in a machine where the film path turns and where the film must be accurately positioned on one or both sides of the turn, as, for example, at 1 and 4 of aforesaid application, Serial 95 No. 512,399.

I claim:

1. In a cinematographic machine, a film-guide extending transversely of the film path and having shoulders engaging the 100 opposite edges of the film, a support, means for adjusting said guide edgewise of the film, and means for angularly adjusting said film-guide.

2. In a cinematographic machine, a film-guiding roller extending transversely of the 105

- film path and having shoulders engaging the opposite edges of the film, a support, means for adjusting said guide edgewise of the film, said means including a threaded 45
5 adjuster having its axis concentric with said roller, and means for angularly adjusting said film-guiding roller.
3. In a cinematographic machine, a film- 10 guide extending transversely of the film path and having shoulders engaging the opposite edges of the film, a stud for said guide extending edgewise of the film, a support having threaded engagement with said stud, means on the stud for restraining 15 movement of said guide longitudinally of said stud, and means for angularly adjusting said film-guide.
4. In a cinematographic machine, a support, a shaft mounted in the support for 20 axial adjustment, a film-guiding roller mounted on said shaft for rotation but held against axial movement relatively to the shaft, and means for angularly adjusting the film-guiding roller.
5. In a cinematographic machine, a shaft, a support for said shaft, a film-guiding roller rotatable on said shaft but retained in 25 fixed axial position thereon, and means for adjusting said shaft axially and angularly 30 relatively to said support.
6. In a cinematographic machine, a shaft, a support having a bearing for said shaft, a film-guiding roller rotatable on said shaft, spaced collars fast on said shaft to retain 35 said roller in fixed axial position thereon, means for adjusting said shaft axially in its bearing, and means for adjusting the position of at least one of said bearings relatively to said support.
7. In a cinematographic machine, a shaft having a film-guiding roller rotatably mounted in fixed axial position thereon, one end of said shaft being threaded, a support having a threaded opening to receive said 40
- threaded end of said shaft whereby said shaft is adjustable axially upon said support, and means for angularly adjusting said film-guiding roller relatively to said support.
8. In a cinematographic machine, a shaft 45 having a film-guiding roller rotatably mounted in fixed axial position thereon, one end of said shaft being threaded, a support having a threaded opening to receive said threaded end of the shaft, means for locking 50 said shaft in adjusted position, and means for adjusting the angular position of the shaft relatively to said support.
9. In a cinematographic machine a support, a film-guiding roller rotatably 55 mounted upon said support, means for axially adjusting said roller about an axis perpendicular to the plane of its axis, and means for angularly adjusting said roller.
10. In a cinematographic machine, a support having spaced ears, said ears having aligned openings forming bearings, a shaft supported in said bearings, a film-guiding roller rotatable in fixed position on said shaft, one of the bearings for said shaft 60 being threaded to cooperate with a threaded portion of said shaft to permit axial adjustment of said shaft and roller, a set screw arranged to engage the threaded portion of said shaft to retain said shaft in adjusted 65 position, and at least one of said ears adjustable relatively to said support.
11. In a cinematographic machine, a film-guiding roller a shaft on which said roller is rotatably supported, a bracket having 70 bearings supporting said shaft, and spaced openings in said bracket for attaching the latter to a support, one of said openings comprising a slot to permit angular adjustment of the bracket relative to the support.
- Signed by me at Boston, Massachusetts, this 27th day of July, 1923.
- LEONARD T. TROLAND.
